CLAIM

I claim the ornamental design for an appliance door latch, as shown and described.

DESCRIPTION

FIG. 1 is a perspective view of an appliance door latch showing my new design, shown in environmental use;

FIG. 2 is an enlarged perspective view thereof.

FIG. 3 is a front elevational view thereof; and,

FIG. 4 is a side elevational view thereof, the other side elevational view being a mirror image thereof.

The broken lines are for illustrative purpose only and form no part of the claimed design.
